UNITED STATES PATENT OFFICE.

EDWARD I. LONG, OF MAYER, ARIZONA.

REFRIGERATOR.

1,307,302.

Specification of Letters Patent. Patented June 17, 1919.

Application filed January 6, 1919. Serial No. 269,896.

To all whom it may concern:

Be it known that I, EDWARD I. LONG, a citizen of the United States, residing at Mayer, in the county of Yavapai and State 5 of Arizona, have invented certain new and useful Improvements in Refrigerators; and I do declare the following to be a full, clear, and exact description of the invention, such as will enable others skilled in the art to 10 which it appertains to make and use the same.

My invention has for its object to provide a simple and rather inexpensive refrigerator or cooling chamber designed principally for 15 domestic use and employing the cooling effect of evaporating moisture, as its refrigerating means. I am aware that numerous devices have heretofore been provided operating on this general principle, but my principal improvement resides in the novel wall 20 construction and means for directing a current of air along both sides of a moist slab in the wall, and for discharging the air thus cooled into the refrigerating chamber, from 25 which it may escape through a vent.

A further object of the invention is to provide an arrangement of tubes and drip cocks for moistening the slab or slabs, so disposed as to act also as a railing around the edge 30 of the refrigerator top, whereby to prevent articles set thereon from falling therefrom.

With the foregoing objects in view, the invention resides in the novel features of construction hereinafter fully described and 35 claimed, reference being made to the accompanying drawing.

Figure 1 is a front elevation partly in section.

Fig. 2 is an end elevation.

Fig. 3 is a top view partly in horizontal section.

Fig. 4 is a horizontal section showing a different shape of casing in which one similarly shaped slab is employed, rather than a 45 number of slabs as in the views before described.

In Figs. 1 to 3 of the drawing, a rectangular form of refrigerator is shown constructed in accordance with the invention, 50 while Fig. 4 discloses a cylindrical type of refrigerator to which the improved features are equally well adapted.

The numerals 1, 2, 3 and 4, represent the 55 four sides of the refrigerator wall in Figs. 1, 2 and 3; 5 designates the top of the casing; 6 has reference to a drip pan forming the

bottom thereof; and 7 has reference to any suitable door for giving access to the interior of the casing, which may be provided with appropriate shelves or racks 8.

The adjacent edges of the sides 1, 2, 3 and 4 are suitably secured in any preferred manner to angle iron corner posts 9 which may be provided with casters 10, and all of said sides are of hollow construction, consisting 65 of spaced inner and outer sheet metal plates 11 and 12, respectively. Between the plates 11 and 12 and spaced downwardly from the upper ends thereof, is a slab 13 of cement or other appropriate absorbent material, one 70 slab being provided for each side of the casing. Any preferred means may be provided for spacing the sides of the slab 13 from the plates 11 and 12, sufficiently to permit the travel of air along said sides of the slabs, 75 but for illustrative purposes I have shown restricted portions of the plates punched inwardly at 14 for this purpose.

A plurality of drip cocks 15 pass through the upper ends of the casing sides and depend from a continuous distributing tube 16 extending around the edge of the refrigerator top. Water is supplied to the tube 16 from a water tank 17 mounted on top of the refrigerator, by means of a valved 80 tube 18 leading from said tank. By opening the valve in the tube 18, the cocks 15 may be supplied with water so that such water in dripping from the cocks will moisten the slabs 13. Air is admitted into 85 the hollow sides through inlet openings 19 in the lower ends thereof, this air traveling upwardly along the outer sides of the moist slabs, then over the upper ends of said slabs, 90 downwardly along their inner sides, and into the refrigerator chamber through air outlet openings 20 formed in the lower ends 95 of the plates 11. In thus passing over the moist slabs, considerable evaporation takes place and thus the air is chilled so that the 100 contents of the refrigerator will be maintained at a low temperature. The air may escape through vents 21 with which the refrigerator top 5 is provided, and it is intended that a continuous circulation of 105 air shall take place along the paths above mentioned, as indicated by arrows in Fig. 1.

In addition to constructing the device of polysided shape, it may well be made in cylindrical form as depicted in Fig. 4, in 110 which case a one-piece slab 13' might well be interposed between the inner and outer

plates 11' and 12' of which the refrigerator wall is formed. This wall will be provided with air inlets and outlets such as those above described and all other features of the refrigerator may remain the same.

From the foregoing, taken in connection with the accompanying drawings, it will be seen that although my invention is of simple and inexpensive nature, it will be highly efficient and in every way desirable, and since probably the best results are obtained from the details shown and described, they may well be followed. It is to be understood, however, that within the scope of the invention as claimed, considerable latitude is allowed for making such minor changes as occasion may dictate.

I claim:

1. In a refrigerator, a casing having a hollow side wall, an absorbent slab in said wall spaced from the sides and upper end thereof, and means for moistening said slab, the lower end of the outer side of said wall having an air inlet, the lower end of the inner side of said wall having an air outlet into the casing, and said casing having a vent in its upper end, whereby air will enter said hollow wall, pass upwardly along the

outer side of the moist slab, then over said slab, downwardly along the inner side of the latter, into the casing, and from the latter through said vent.

2. In a refrigerator, a casing having a hollow side wall, an absorbent slab in said wall spaced from the sides and upper end thereof, a water tank mounted on the upper end of said casing, a water outlet tube leading from said tank, a water distributing tube into which said outlet tube discharges, and drip cocks depending from said distributing tube through the upper end of said wall for delivering water to moisten said slab, the lower end of the outer side of said wall having an air inlet, the lower end of the inner side of said wall having an air outlet into the casing, and the upper end of the latter having a vent, whereby air will enter said hollow wall, pass upwardly along the outer side of the moist slab, then over said slab, downwardly along the inner side of the latter, into the casing, and from the latter through said vent.

In testimony whereof I have hereunto set my hand.

EDWARD I. LONG.
